UNITED STATES PATENT OFFICE.

ROBERT D. BERG, OF ST. PAUL, MINNESOTA.

TRACK-DRILL.

1,101,114.

Specification of Letters Patent. Patented June 23, 1914.

Application filed September 24, 1912. Serial No. 722,030.

To all whom it may concern:

Be it known that I, ROBERT D. BERG, of St. Paul, Ramsey county, Minnesota, have invented certain new and useful Improvements in Track-Drills, of which the following is a specification.

My invention relates to power operated machines for drilling track rails and the object of the invention is to provide a machine adapted particularly where a large amount of drilling is required, as when new rails are laid or when anti-creepers are put on the track.

A further object is to provide a machine which can be easily and quickly moved from place to place on the track and by means of which holes can be accurately and quickly drilled in the rails.

A further object is to provide a machine which is adapted to run on the track but can be readily lifted off the rails whenever desired.

The invention consists generally in various constructions and combinations, all as hereinafter described and particularly pointed out in the claims.

In the accompanying drawings forming part of this specification, Figure 1 is a plan view of a track drilling machine embodying my invention, Fig. 2 is a side elevation of the same, Fig. 3 is a front elevation of a portion of the machine, showing the manner of mounting the drills thereon, Fig. 4 is a detail view, showing the tilting drill carrier, Fig. 5 is a detail sectional view, showing the means for feeding the drill, Fig. 6 is a detail sectional view, showing the train of gears between the driving shaft and the drill spindle, and the means for supporting the drill carrier on the machine, Fig. 7 is a detail sectional view, showing the driving connection between the engine shaft and the drill carrier gears, Fig. 8 is a detail view showing the manner of mounting the drill carriers on their shaft.

In the drawings, 2 represents the track rails.

3 is a frame, preferably of cast metal, having bearings on axles 4 and 5 which are provided with carrying wheels 6 and 7. These wheels are adapted to rest and roll upon the track rails.

8 represents a gas engine, mounted on the frame 3 and having a shaft 9 running lengthwise of the machine and provided at its rear end with the usual fly wheel 10.

11 represents a water circulating system for the engine and 12 is a gasoline tank.

The forward end of the engine shaft projects in front of the machine frame and is provided with a worm 13 arranged within a suitable casing or housing 14. This worm meshes with a gear 15 that is mounted on a transverse shaft 16 which extends from side to side of the machine at right angles to the engine shaft. (See Fig. 1). The shaft 16 has bearings in brackets 17 provided on the forward portion of the machine frame. The forward portion of the machine frame preferably has upwardly turned portions thereon forming standards 18 whereto a transverse plate 19 is secured. This plate has beveled longitudinal edges and forms a guide for the carriages 20, which are adapted to slide back and forth thereon on each side of the machine for the purpose of moving the drills toward or from the work. Any suitable means may be employed for moving these carriages, but I prefer to provide screw shafts 21 mounted in bearings 22 on the plate 19 and engaging the threaded openings in the carriages 20, so that when the screw shafts are revolved by means of the cranks 23 the carriages will be moved transversely with respect to the machine. The carriages 20 have forwardly projecting lugs or ears 24 thereon. Drill carriers 25 have similar ears 26 adapted to slip in between the ears 24. Sleeves 27 are slidable on the shaft 16 and have threaded inner ends adapted to engage the interiorly threaded ears 24 and fit loosely within the ears 26 to allow the drill carriers to swing forwardly and upwardly, independently of the carriages, and also be capable of a transverse sliding movement on the shaft 16 when the screw shafts 21 are operated. Gear wheels 28 are mounted on the shafts 16 and through a train of gears 29 operate gears 30 on the drill spindles 31. These spindles are adapted to receive drills 32. These drills with the carriers are adapted to swing forwardly and upwardly and on the upper portion of the carriers I prefer to provide pivoted arms 33 having curved bearing faces 34 at one end which are adapted to contact with the forward axle 5 and hold the drill carriers in a raised, inoperative position, as indicated by full lines in Fig. 4. When these arms are allowed to drop down to a vertical position the carriers will swing down and assume a substantially upright position, ready for the drilling operation.

For the purpose of changing the angle of the drill carriers with respect to the ground line, I prefer to provide adjusting screws 35 mounted in the drill carriers and adapted to contact with the forward portion of the machine frame, so that the operator, by revolving these screws, can swing the carriers on their pivots and raise or lower the drills. I also prefer to provide levers 36 mounted on the drill carriers by means of which they can be easily and quickly tilted on their pivots. The drill spindles have a splined connection with the gears 30 to slide freely therein and turn when the gears 30 are revolved. One end of the spindle is provided with a drill socket 37 to receive the end of the drill and at the other end of the spindle is a sleeve 38 secured on the spindle by a lock nut 39 and provided with a rack 40 which meshes with a pinion 41 secured on a shaft 42. A disk 43 is secured on said shaft and has a series of sockets 44 therein to receive an operating lever 45. The rocking of this lever will move the spindle and feed the drill to the rail. The drills may be operated simultaneously or independently of one another, as desired, the adjustment toward and from the work being easily and quickly performed by means of the screw shafts 21 and 30 the feed of the drills being accurately regulated by the rack and pinion mechanism described. Both drill spindles will be operated simultaneously through the driving connection of the shaft 16 with the engine shaft, but either one of the drill carriers may be swung to an inoperative position or it may be set at a point where the drill will be out of contact with the rail, or if the work is to be performed mostly on one side of the car the drill on the other side can be entirely removed from its socket. In the operation of the machine, the end thrust of the drill will be taken up by the flanges of the carrying wheels.

For the purpose of sharpening the drills conveniently, I prefer to provide an emery wheel 46 mounted on a spindle 47 having a pulley 48 thereon that is belted to the fly wheel or to some moving part of the machine. The emery wheel is preferably provided at the rear portion of the car on a suitable bracket 49.

In the operation of the machine, the car is set at a point where the drilling is to be performed, the drill placed in its socket and the carriage lowered to the desired level. The carrier and carriage being moved to their working position the engine is started and the drill fed into the rail until the work is complete. When either drill carrier is not in use it may be swung up and supported in its raised, inoperative position.

I claim as my invention:—

1. The combination, with a car frame having carrying wheels and a source of motive

power mounted thereon, of a transverse shaft having a driving connection with said source of motive power, a carriage slidable transversely of said frame parallel with said transverse shaft, a pivoted drill carrier having an oscillating movement in a vertical plane at right angles substantially to the direction of movement of said carriage and a transversely sliding movement with said carriage, a drill spindle having a driving connection with said shaft, a drill mounted in said spindle, means for moving said carriage and carrier transversely of said car, and means for feeding said drill.

2. The combination, of a frame having carrying wheels and a gas engine mounted on said frame, a transverse shaft having a driving connection with the engine shaft, a drill carrier pivotally connected to one end of said frame and adapted to swing in a vertical plane on its pivot and having a sliding movement transversely with respect to said frame, a drill spindle mounted in said carrier and having driving connections with said shaft, means for moving said carrier transversely of said car, a drill mounted in said drill spindle, and means for feeding said spindle and drill to the work.

3. The combination, with a car having carrying wheels and an engine mounted thereon, of a transverse shaft having a driving connection with the engine shaft, a pivoted carrier having a sliding movement transversely of said car and adapted to swing on its pivots to a raised, inoperative position, means for supporting said carrier in its raised position, a drill spindle mounted in said carrier, a driving connection between said drill spindle and said shaft, means for moving said carrier transversely of said car, a drill mounted in said spindle, and means for feeding said spindle and drill to the work.

4. The combination, with a car having carrying wheels and a source of motive power mounted thereon and provided with a driving shaft, of pivoted drill carriers mounted to slide transversely of said car and adapted to swing in a vertical plane, drill spindles mounted in the lower portions of said drill carriers and having driving connections with said shaft, means for tilting said carriages on their pivots to raise or lower said drill spindles, drills mounted in said spindles, and means for feeding said spindles and drills to the work.

5. The combination, with a car having carrying wheels and a source of motive power mounted thereon and provided with a driving shaft, of a transverse shaft geared to said driving shaft, pivoted drill carriers adapted to swing in a vertical plane and also move lengthwise to said transverse shaft, spindles mounted in the lower portions of said carriers and having driving

connections with said shaft, means engaging said car for swinging said carriers forwardly and upwardly on their pivots to raise or lower said drill spindles, drills carried by said spindles, and means for feeding said spindles and drills to the work.

6. The combination, with a car frame having carrying wheels and a source of motive power mounted thereon provided with

10 a driving shaft, of a transverse shaft geared to said driving shaft, a transverse plate secured to the forward portion of said frame, carriages slideable lengthwise on said plate and transversely of the machine, drill carriers connected with said carriages to slide transversely therewith, means for operating said carriages to move them and said carriers simultaneously, said carriers being adapted to swing independently in vertical

15 planes, drill spindles mounted in said carriers and having driving connections with said transverse shaft, drills mounted in said spindles, and means for moving said spindles lengthwise to feed said drills to the

20 work.

7. The combination, with a frame having carrying wheels and a source of motive power mounted thereon provided with a driving shaft, of transversely slideable carriages and a guide therefor and means for moving said carriages, said carriages having forwardly projecting ears, drill carriers also having ears concentric with the ears of said carriages, a shaft passing 25 through the ears of said carriages and carriers and geared to said driving shaft, said carriers having a transverse sliding movement with said carriages and an independent oscillating movement, spindles mounted 30 in said carriers and having driving connections with said transverse shaft, the oscillation of said carriers raising or lowering said spindles, drills mounted in said spindles and means for moving said spindles 35 lengthwise to feed said drills to the work.

8. The combination, with a frame having carrying wheels adapted to rest upon the railroad rails, and a source of motive power mounted on said frame, of a drill carrier 40 movable transversely of said frame between said wheels, mechanism for moving said carrier back and forth across said frame toward or from either track rail, a drill spindle mounted in said carrier and having 45 a driving connection with said source of motive power, a drill mounted in said spindle and having means for feeding it toward or from the track rails, said carrier being free to swing vertically to raise or lower 50 the operative position of said drill with respect to said rails.

9. The combination, with a car frame having carrying wheels and a source of motive power, of carriages mounted to move 55 on said frame transversely thereof, screw

shafts for feeding said carriages, drill carriers pivotally supported on said carriages and movable transversely therewith and having freedom of vertical movement on their pivots, drill spindles mounted in said 70 carriers and having driving connections with said source of motive power, drills for said spindles, and means for feeding said drills to the work.

10. The combination, with a car frame 75 having carrying wheels and a source of motive power, of a drill carrier pivotally supported on said frame, and free to move transversely thereon, a transverse screw shaft for moving said carrier back and forth across the car, said carrier being free to swing vertically on its pivots, a drill spindle mounted in said carrier and having a driving connection with said source of motive power, a drill for said spindle, 80 means for feeding said drill to the work, and means for tilting said carrier on its pivots to change the elevation of said drill for drilling holes on different levels.

11. The combination, with a car frame 90 having carrying wheels and a source of motive power mounted on said frame, of drill carriers pivotally supported on said frame, screw shafts mounted to move said carriers back and forth transversely of said frame, 95 said carriers being free to swing vertically on their pivots at right angles substantially to their transverse movement, drill spindles mounted in said carriers and having driving connections with said source of motive 100 power, drills for said spindles, means for feeding said drills to the work, the drill on one side of the machine when in contact with the work taking up the thrust of the drill in operation on the other side of the 105 machine.

12. The combination, with a frame and a source of motive power, of a carriage movable transversely in said frame, a drill carrier mounted in said carriage to move transversely therewith, said carrier having a vertical swinging movement independently of its transverse movement with said carriage, a drill mounted in said carrier, transversely thereof and of said frame and having a 110 driving connection with said source of motive power, and means for feeding said drill to the work.

13. The combination, with a frame and a source of motive power thereon, of carriages 115 arranged upon opposite sides of the middle portion of said frame and movable transversely thereof, and mechanism for operating said carriages, carriers supported by said carriages and movable transversely 120 therewith and also having freedom of vertical swinging movement, drills mounted in said carriers and operatively connected with said source of motive power, means for feeding said drills to the work transversely of 125 130

said frame and carriers, and means for swinging said carriers to raise or lower said drills.

14. The combination, with a wheeled frame, of drill carriers pivotally supported thereby, screw shafts for feeding said carriers back and forth transversely of said frame, said carriers being free to swing vertically on their pivots, drill spindles mounted in said carriers, a source of motive power having driving connections with said drill spindles, drills for said spindles, and means for feeding said drills to the work

15. The combination, with a wheeled frame and drill carriers pivotally supported thereon, of means for feeding said carriers back and forth, transversely of said frame, said carriers being free to swing vertically on their pivots, drill spindles mounted in 20 said carriers, a source of motive power having driving connections with said drill spindles, drills for said spindles, means for feeding said drills to the work, and means for tilting said carriers on their pivots to raise 25 or lower the working position of said drills.

16. The combination, with a frame, of drill carriers pivotally supported thereon, means for feeding said carriers transversely of said frame, said carriers being free to 30 swing vertically on their pivots, drill spindles mounted in said carriers, a source of motive power having driving connections with said drill spindles, drills for said spindles, means for feeding said drills to the 35 work, said carriers being adapted to swing to a raised, inoperative position, and means for supporting them in their raised position.

17. The combination, with a frame having carrying wheels adapted to roll upon railroad rails, of drill carriers pivotally supported by said frame and free to swing vertically thereon, drill spindles mounted in 40 said carriers, a source of motive power having driving connections with said drill spindles, drills for said spindles, means for feeding 45 said drills to the work, and means for

tilting said carriers to raise or lower the working position of said drills.

18. The combination, with a frame having carrying wheels and a source of motive power, of a drill carrier movable transversely of said frame, a drill spindle mounted in said carrier and having a driving connection with said source of motive power, a drill mounted in said spindle and having a feeding means, said carrier being free to swing vertically to raise or lower the operative position of said drill, and adjusting screws mounted in said carrier and adapted to engage said frame, for the purpose specified.

19. The combination, with a frame having carrying wheels and a source of motive power, a drill carrier movable transversely of said frame, a drill spindle mounted in 65 said carrier having a driving connection with said source of motive power, a drill mounted in said spindle and said carrier being free to swing vertically to raise or lower the operative position of said drill and also 70 swing to a raised, inoperative position, and a pivoted arm arranged to support said carrier in such raised, inoperative position.

20. The combination, with a frame having carrying wheels adapted to rest upon the railroad rails, of a drill carrier movable transversely of said frame, mechanism for moving said carrier, a drill spindle mounted in said carrier and driving means for said 80 drill spindle, a drill mounted in said spindle having means for feeding it toward or from the track rails, said carrier being free to swing vertically to raise or lower the operative position of said drill with respect to said rails.

In witness whereof, I have hereunto set my hand this 17th day of September, 1912.

ROBERT D. BERG.
